No. 889,890.

PATENTED JUNE 9, 1908.

H. B. BASS.

GUN CLEANING ROD.

APPLICATION FILED SEPT. 16, 1907.

UNITED STATES PATENT OFFICE.

HARRY B. BASS, OF YUKON, OKLAHOMA.

GUN-CLEANING ROD.

No. 889,890.

Specification of Letters Patent.

Patented June 9, 1908.

Application filed September 16, 1907. Serial No. 393,202.

To all whom it may concern:

Be it known that I, HARRY B. BASS, a citizen of the United States, residing at Yukon, in the county of Canadian and State of Oklahoma, have invented a new and useful Gun-Cleaning Rod, of which the following is a specification.

This invention relates to cleaning rods for guns, rifles and other fire-arms and has for its object to provide a comparatively simple, inexpensive and efficient device of this character by means of which the interior of a gun barrel or other fire arm may be effectually cleaned.

A further object of the invention is to provide a cleaning rod having a spirally disposed groove formed in the walls thereof for the reception of a cloth or other cleaning medium thereby to prevent said cleaning medium from sliding longitudinally of the rod during the cleaning operation.

A further object is to form the rod with oppositely disposed slots or openings for anchoring the adjacent ends of the cleaning medium in position on the rod, one of said slots being intersected by the spiral groove.

A still further object of the invention is generally to improve this class of devices so as to increase their utility, durability and efficiency as well as to reduce the cost of manufacture.

Further objects and advantages will appear in the following description, it being understood that various changes in form, proportion and minor details of construction may be resorted to within the scope of the appended claims.

In the accompanying drawings forming a part of this specification: Figure 1 is a perspective view of a cleaning rod constructed in accordance with my invention. Fig. 2 is a similar view of the lower portion of the rod showing the cleaning medium in position thereon. Fig. 3 is a transverse sectional view taken through the cloth receiving slot. Fig. 4 is a transverse sectional view through the grooved portion of the rod. Fig. 5 is a detail perspective view of the lower end of the rod.

Similar numerals of reference indicate corresponding parts in all of the figures of the drawings.

The improved device forming the subject matter of the present invention includes a cylindrical bar or rod 5 having one end thereof curved to form a terminal loop constituting

a finger piece 6 by means of which the device may be conveniently manipulated.

The walls of the rod at the lower end thereof are provided with a spirally disposed groove 7 which extends approximately one-third the length of the rod and is adapted to receive a strip of cloth or other cleaning medium 8.

Formed in the lower end of the rod 5 is an elongated transverse slot 9 which is intersected by the spiral groove 7 and constitutes an anchoring member for the adjacent end of the cleaning medium 8, there being a similar slot 10 formed in the rod at the opposite end of the spiral groove, as shown. It will thus be seen that the groove 7 serves to hold the cleaning medium 8 in position on the active end of the rod during the cleaning operation thereby to prevent bunching of the cloth within the gun barrel while the transverse slots 9 and 10 form anchoring means for the opposite ends of the cleaning cloth.

By having the lower slot 9 intersected by the spiral groove the cloth may be readily guided to the groove by simply holding one end of the cloth and rotating the rod between the fingers, as will be readily understood.

It will of course be understood that the spiral groove may extend to any desired height on the rod and that the pitch of said groove may be varied at will so as to conform to the inclination or pitch of the grooves of different rifle barrels.

The cleaning rod may be made in different sizes and shapes and may be nickelized or otherwise coated or plated to give the same a neat appearance and to prevent the metal from corroding.

From the foregoing description it will be seen that there is provided an extremely simple, inexpensive and efficient device admirably adapted for the attainment of the ends in view.

Having thus described the invention what is claimed is:

1. A cleaning rod having a spiral groove formed in the walls thereof for the reception of a cleaning medium, there being slots formed in the rod for anchoring the opposite ends of the cleaning medium, one of said slots being intersected by the spiral groove at the active end of the rod.

2. A cleaning rod having one end thereof provided with a finger piece and its opposite end formed with a spiral groove extending

- approximately one-third the length of the rod for the reception of a cleaning medium, there being transverse slots formed in the rod for anchoring the opposite ends of the 5 cleaning medium, one of said slots being disposed between the finger piece and the adjacent end of the groove and the other intersected by said groove at the active end of the rod.
- 10 3. A cleaning rod having one end thereof provided with a finger piece and its opposite end formed with a spiral groove, there being a transverse slot formed in the rod at each 15 end of the spiral groove, one of said slots being spaced from the groove and the other

intersected by said groove, and a strip of flexible material having one end thereof threaded through the lower slot, and an intermediate portion seated within and curved to conform to the spiral groove, the terminal 20 of said flexible strip being extended transversely through the adjacent slot.

In testimony that I claim the foregoing as my own, I have hereto affixed my signature in the presence of two witnesses.

HARRY B. BASS.
